Application August 23, 1947, Serial No. 770,268

12 Claims. (Cl. 201—51)

1

This invention relates to improvements in electric regulators of the carbon pile type and more particularly to carbon pile regulators such as are used on automotive vehicles wherein the generator is employed to charge the storage battery.

An object of the present invention is to provide a compact, easily adjusted and highly effective automatic regulator for varying the resistance in response to the flow of current through a certain circuit.

Another object of the present invention is to provide spring means for controlling the pressure exerted on a pile of carbon discs and opposing the force of the magnet which is so constructed and arranged that the force exerted thereby increases at the same rate as the force exerted by the magnet increases upon decrease in the air gap.

Another object is to provide resistance compression means including a magnetically rockable member and a movable contactor operatively connected with the rockable member and interposed between the rockable member and one end of the resistance which will vary the compression of the resistance in response to relatively small movements of the rockable member.

Another object of the invention is to provide a radiator for a carbon pile regulator which will dissipate heat from the carbon pile.

Further objects and advantages of the present invention will be apparent from the following description, reference being had to the accompanying drawings wherein a preferred embodiment of the present invention is clearly shown.

In the drawings:

Fig. 1 is a top plan view of a voltage regulator.

Fig. 2 is a sectional view taken in line 2—2 of Fig. 1.

Fig. 3 is a bottom plan view of the regulator shown in Fig. 1.

Fig. 4 is a side view looking in the direction of arrow 4 of Fig. 2.

Fig. 5 is a sectional view on line 5—5 of Fig. 1.

Fig. 5A is a modified form of the spring structure shown in Fig. 5.

Fig. 6 is a sectional view on line 6—6 of Fig. 2.

Fig. 7 is a sectional view on line 7—7 of Fig. 2.

Fig. 8 is a plan view of a current regulator.

Fig. 9 is a sectional view taken on line 9—9 of Fig. 8.

Fig. 9A is a sectional view showing a modified construction and arrangement of carbon discs.

Fig. 10 is a plan view of cooling means associated with the regulators in accordance with the present improvements.

2

Fig. 11 is a sectional view taken on line 11 of Fig. 10.

Fig. 12 is a wiring diagram of a generator regulating system embodying the present invention and shows particularly the arrangement of the regulators and other electrical instruments with which the generator and a battery are connected.

Referring to Figs. 1 to 7, inclusive, a detail structure of a voltage regulator 20 will be described.

10 The voltage regulator comprises a housing 21, of good thermal conductivity, such as aluminum having a through opening 22 to receive a refractory insulating tube or sleeve 23 which houses a compressible resistance such as a stack of carbon discs 24.

The housing 21 supports a subassembly including a metallic U-shaped mounting bracket 25 and a metallic U-shaped frame 26 as shown in Fig. 6. In this construction arms 27 of the frame 26 are secured to arms 28 of the bracket by a series of rivets 29. Parts 25 and 26 are magnetizable. The arms 28 of the mounting bracket 25 are provided with ears 30 which are bent at an angle to the normal plate of arms 28 and toward each other. Plates 31 are attached to ears 30 in any suitable manner, as by spot-welding, in order to provide extra thickness. The ear and plates are tapped to receive the threaded ends of screws 32 which attach the frame 25 to the base 21.

30 The yoke 35 of the frame 26 is provided with an opening for receiving a reduced portion 36 of a magnetizable core 37. The core 37 is attached to the yoke 35 by riveting over the reduced portion 36 against a magnetizable washer 38. The core 37 supports a coil assembly including a winding 40 of fine wire about a brass tube 41 surrounded by a sleeve of insulating material. The ends of the tube 41 are bent radially outward against respective insulating washers 42 located

35 around the tube and bearing against an insulating sleeve 42a. A metallic stop washer 43 is press fitted over the free end of core 37 to hold the coil assembly thereon. The coil assembly is urged against the stop washer 43 by a coil spring or 40 resilient member 44 disposed between the innermost washer 42 and the yoke 35.

The armature assembly for the regulator comprises a U-shaped hinge support 50 (Figs. 2 and 7) having a yoke 51 provided with an opening 52.

50 The side arms 53 of the hinge support are provided with elongated openings 54, (Figs. 4 and 7) to permit adjustment of the support 50 relative to the frame 26. Screws 55 pass through the openings 54 and have threaded engagement with 55 tapped holes in the frame 26. The screws 55 will,

when tightened, secure the hinge support 50 to the frame 26 in the desired position of adjustment. The hinge support 50 is provided with an ear 56 (Fig. 2) bent at an angle from the normal plane of the yoke.

An armature 60 is hingedly connected with the ear 56 by a flexible bi-metal strap 61 to compensate for change in temperature. One end of the strap 61 is secured to the armature 60 by rivets 62. The other end of the strap 61 is provided with elongated openings to receive screws 64, which pass through the openings and have threaded engagement with tapped holes in the ear 56. When the screws 64 are tightened they will secure the strap to the ear in the desired position of adjustment.

A rockable U-shaped arm 70 is attached to the armature 60. The arm 70 includes a yoke 71 provided with a tapped opening 72 and a plain opening 73 and having side branches 74 provided with spaced openings 75. The side branches are provided with ears 76 bent toward each other and attached to the armature 60. Certain of the rivets 62 which secure the strap 61 to the armature also pass through the ears 76 and are peened over against the outer surface of the ears 76 and thus assist in securing the ears 76 to the armature 60. Ears 76 are attached to armature 60 also by screws 77 which are screwed into armature 60.

Referring to Fig. 4, it will be noted that the spaced openings 75 are larger in dimensions than the head of the screws 55 thus permitting a tool, such as a screwdriver, to loosen the screws 55 so that hinge support 50 can be adjusted relative to the arms 26 to vary the gap between the armature 60 and the core 37.

Vibrations of the armature are damped by a dash pot which includes a plate support 81 having a series of openings through which bolts 82 extend. The bolts 82 pass through spacer sleeves 83 and enter tapped openings in the yoke 71. A cylinder 84 having an outwardly extending flange 85 is secured to the plate support 81. Disposed centrally within the cylinder 84 and centrally is one end of a rod 86 which carries a disc 87 the periphery of which closely fits the annular wall of the cylinder 84. A flexible disc 88 which is attached to flange 85 of cylinder 84 and to the rod 86 closes the cylinder 84. The space between the disc 88 and the back wall of the cylinder is completely filled with oil which is sealed in by a plain ring 89 and a corrugated ring 90 of spring metal secured together with the periphery of disc 88 against the flange 85 by a clamping ring 91. Disc 88 is made of oil resisting material such as neoprene.

The cylinder 84 is movable relative to the disc 87, the movement of the rod 86 being prevented by having the rod pass through the opening 73 in the arm 70 and having the other end attached to a self-aligning bearing comprising a cage 95 and a ball 95a. Cage 95 is attached to the stationary yoke 25 by a plate 96 secured by screws 97. The rod 86 is secured to the ball 95a by a nut 93 threaded on the end of rod 86 which passes through the ball.

As shown in the drawings the regulator thus far described includes compressible resistance or carbon discs pile 24 housed within the ceramic sleeve 23 located within the opening 22 of the housing 21. One end of the carbon discs pile is engaged by a contactor 101. The contactor has a spherical portion which is engaged by a contact 102 carried by a terminal screw 103 threadedly

mounted in a plate 104. A lock nut 105 is provided to maintain the screw 103 fixed. The plate 104 is provided with an aperture through which the rod 86 projects. The plate is insulatingly supported from the arm 70 by insulating strips 106. The other end of the stack of carbon discs is engaged by a contactor 107 carried by an adjustable terminal screw 108. The terminal screw 108 is attached to a metallic internally threaded bushing 109 which is received by a plain opening in a contact support bracket 110. In this instance the bushing has a reduced portion projecting through an opening in the contact support bracket 110 and spun over the lower face thereof. The bracket 110, rests upon the housing 21 but is insulated therefrom by an insulating strip 111. The contact support bracket 110 is fixed to the housing 21 by screws 112 having threaded engagement with tapped holes provided in the housing.

The carbon pile 24 is normally placed under compression by adjustable tension springs 115 (Fig. 5) each having one end thereof hooked over a pin 116 attached to an ear 117 formed on the arm 70. The other end of each spring 115 is hooked over a pin 118 fixed to a stud 119. The studs 119 are of rectangular cross section and have a sliding fit in corresponding openings in sleeve 120, fixed to the yoke of bracket 25 in any suitable manner. Each stud is provided with a reduced threaded portion 121 which extends through the sleeve 120 and is in screw-threaded engagement with an adjusting nut 122. By turning the nuts 122 the initial tensions of the springs 115 are adjusted. The springs 115 urge the arm 70 counterclockwise (Fig. 2) relative to the hinge bracket flange 56 thereby causing the contact 102, carried by the plate 104, to bear against the contactor 101 to compress the carbon pile 24 between the contacts 101 and 107.

The coil springs 115 have given satisfactory results when regulation requires a limited movement of the regulator armature. If the condition of service is such as to require a relatively great movement of the armature, springs 123 of the type shown in Fig. 5A can be substituted for the coil springs 115. The springs 123 are of flat stock and bent in and out as substantially shown in Fig. 5A. One end of the springs fit into a slot formed in the studs 119 and fixed therein by a rivet 124. The other end of the springs are fixed to the ears 117 by rivets 125. The springs 123 are constructed so as to oppose magnetic pull by forces which increase substantially in proportion to the increase of magnetic pull as the gap between the armature and the core decreases. Springs 123 are of the same type as those disclosed in our application S. N. 646,675 filed February 9, 1946.

The yoke of the mounting bracket 25 is utilized to provide a mechanical support for a block 126 of insulating material for supporting headed terminal screws 127, 128 and 129. The terminal screws extend through counterbored openings provided by the block, the beads of the terminal screws being insulated from the yoke of bracket 25 by a sheet of insulation disposed between the block and the yoke. The block 126 is attached to the bracket 25 by screws 126a.

The regulator described heretofore can be used as a voltage regulator. Fig. 9 illustrates a current regulator 130, comprising a construction somewhat similar to the construction of the voltage regulator illustrated in Figs. 1 to 7. In Fig. 9, the core 37 supports a winding 132 of relatively heavy wire of relatively few turns. The yoke of

the bracket 25 supports an L-shaped block 135 of insulating material which is secured to the yoke by screws 136. One arm 137 of the block 135 supports terminals 138 and 139 while the other arm 140 supports terminal 141. One end of the winding 132 is connected to the terminal 138 while the other end of the winding 132 is connected to the terminal 139.

The current regulator 130 and the voltage regulator 20 are housed and supported within a metallic container a wall 145 of which is shown in Fig. 11. The housings 21 of the regulators project through openings 146 in wall 145 and are attached by screws 149a to a heat radiator 147 of aluminum or other good heat conducting material which has radiating fins 148, and which is attached to the wall 145 by screws 149, there being a heat insulating gasket 150 between the radiator and the box wall 145. The construction provides for dissipation of heat from the carbon piles.

For an understanding of the operation of the voltage regulator 20 and the current regulator 130 reference may be had to the circuit diagram Fig. 12 which shows one way in which the regulators may be connected in a circuit. A generator 160 which is driven at variable speed by a vehicle engine, is provided with an armature 161 brushes 162 and 163 and a field winding 164. The generator supplies current to the main circuit, indicated by heavy lines, across which circuit a storage battery 187 is connected to be charged by the generator. The brush 162 of the generator is connected with the terminal 138 by a lead 166. The terminal 138 is connected by a lead 167 to one end of the coil 132 of the current regulator 130. The other end of the coil 132 is connected with the terminal 139. A coil 171 of an actuating relay 172 is connected with a contact 184 of cutout relay 180. The relay 180 has an armature, not shown, carrying a strap 181 supporting contacts 182 and 183 normally separated from contacts 184 and 185 and adapted respectively to engage them. Contact 185 is connected with a lead 186 with terminal of the battery 187. The strap 181 is connected by a lead 188 with a junction of magnet coils 189 and 190 of relay 180. The coil 189 of relatively few turns of low resistance is connected with a terminal 191 of the actuating relay 172. The magnet coil 190 of a relatively large number of turns of relatively high resistance is connected with ground.

The actuating relay 172 has its coil 171 connected in series between the terminal 139 and the contact 184 of the cutout relay. The armature 192 carries straps 193 and 194, separated by insulation. The strap 194 is grounded. The straps 193 and 194 carry, respectively, contacts 195 and 196. Contact 195 is normally separated from stationary contact 198. Both contacts 197 and 198 are connected by leads to terminal 191.

The operation of the actuating relay 172 and the cutout relay 180 is as follows: When generator is not operating the upper contacts 196, 198 of the actuator relay 172 are closed and the lower contacts 195—197 are open. When the generator begins to operate current will flow from brush 162, wire 166, terminal 138, coil 132, terminal 139, coil 171, contact 184, lead 201, variable resistance 200, coil 40 to ground. When the voltage reaches a predetermined value the coil 171 will be energized sufficiently to attract the armature 192 and close contacts 195, 197 and open contacts 196, 198. The closing of the contacts 195, 197 connects the cutout relay windings 189, 190 across the generator. The energization of

the windings 189 and 190 attracts the armature 181 to close contacts 182, 184 and contacts 183, 185 and complete a circuit between the generator and the battery 187. This circuit will remain completed although the generator voltage may not be sufficient for the coil 171 to hold the contact 195 in engagement with the contact 197 provided, however, the energization of coil 171 is not so weak that contact 196 touches the contact 198. Altho contact 195 may separate from contact 197 and render coil 189 ineffective, coil 190 still remains effective to hold the armature 181 down because coil 190 is still connected with the generator through contacts 182, 184. When the generator voltage drops so low that it practically equals battery voltage, the battery coil 171 is not energized, and contact 196 engages contact 198, and coil 189 bucks coil 190 and the magnetism of relay 180 becomes too weak to hold the armature 181 down. Thus the armature is released by spring tension to separate the contacts 182, 184 and 183, 185. This prevents the battery from discharging back through the generator. The generator 160 has its shunt field winding 164 in series with terminal 165, carbon pile 24' of the current regulator 130, the carbon pile 24 of the voltage regulator 20 and terminal 138, which is connected with brush 162 of the generator. The present system of regulation provides controlling the resistance of the various carbon piles therein. The resistance of the carbon pile 24 is controlled by a coil 40 responsive to variation in generator voltage, altho the voltage drop across the coil 40 is less than voltage across the generator brushes. The coil 40 surrounds a core 37 cooperating with the armature 60 attached to a bracket 70. Springs 115 attached to the bracket 70 and the studs 119 urge the movable contactor 102, movable with the bracket, against the pile 24 to exert a predetermined initial pressure on the pile. As generator voltage increases, the coil 40 becomes more effective to oppose the springs 115 and thereby reduce the pressure between the carbon pile discs and thus increase the resistance and voltage drop across the pile 24.

The resistance of carbon pile 24' is controlled by a coil 132 responsive to charging current. The coil 132 surrounds the core 131 which cooperates with the armature 60 attached to the bracket 70 in a manner similar to that described by the voltage regulator. The springs 115 urge the movable contactor against the pile 24' to exert a predetermined initial pressure on the pile 24'.

If the generator 160 is drawn by a vehicle-propelling engine whose speed does not vary greatly, the carbon pile regulators 20 and 130 will operate satisfactorily to control the generator output. However, if the generator is used with an engine whose speed varies over a relatively wide range, it is desirable to use an additional regulator 210 whose function is to variably by-pass current around the shunt field winding 164 in order that the voltage regulator, in particular, may be relieved of the duty of causing its pile 24 to place an exceptionally high resistance in the circuit of the shunt field winding to maintain the field strength within proper bounds at high generator speed.

Fig. 12 shows the by-passing regulator 210 diagrammatically. It includes a carbon pile 213 which normally has high resistance since the discs, which are washer-like, are located between a fixed electrode 235, and a movable electrode 240,

the latter being operatively connected with a rod 234 attached to a lever 70 carrying an armature 60 as is the case of regulators 20 and 130. The springs 115 which urge the armature 60 away from the core 37' also urge the electrode 240 away from the fixed electrode 235. As the voltage impressed on coil 250 which surrounds core 37' increases, the resistance of the pile 213 decreases and therefore, its current carrying ability increases. Pile 213 is in shunt with the field winding 164. Coil 250 is in shunt with the piles 24 and 24' and is responsive to the difference between generator voltage and field voltage drop. As generator speed increases to its maximum value, coil 250 becomes increasingly effective to decrease the resistance of pile 213 which becomes increasingly effective to by-pass current from the field winding 164. Voltage drop across the field is determined by the generator speed and output so the shunt regulator 210 does not have any effect on voltage drop in the field or in the main regulating carbon piles 24 and 24'. However, since the shunt regulator 210 does increase the current through the regulator piles, the resistance required of these piles is reduced by its action. This means that, in the higher speed range, the voltage drop across the piles 24 and 24' is secured without materially increasing the resistance in piles 24 and 24'. Therefore piles 24 and 24' are relieved of the duty of maintaining the resistance within a relatively wide range.

At low speeds, the regulators 20 and 130 can perform better without the by-pass pile 213. Therefore relay 220 is provided. Its core 221 is surrounded by a coil 222 connected with armature support 223 and with pile 24. Support 223 is connected with pile 24'. Coil 222 is responsive to voltage drop across piles 24 and 24'. When the voltage attains a certain value, the armature 224 moves down to close contacts 226 and 227 thereby causing pile 213 to become effective.

The construction of the housing 211 (Fig. 9A) of the regulator 210 is similar to that of housing 21. In this instance the housing for the regulator 210 has a through opening to receive a ceramic tube 232. The stack of apertured carbon discs 213 are housed within the tube 232. The stack of carbon discs surround the rod 234 (also Fig. 12) the ceramic tube 232 maintains the discs in aligned relation. The rod also extends through an apertured contactor 235 (electrode 235 in Fig. 12) fixed to the housing 231 by screws, not shown. One end of the rod 234 is provided with a reduced threaded portion which extends through a self-aligning bearing unit 236 carried by a plate 237 insulatingly supported on an arm 70 not shown in Fig. 9A. The other end of the rod has a head 238 which bears against a resilient dish-shaped washer 239 that bears against an apertured metallic washer 240 (electrode 240 in Fig. 12) contacting one end of the carbon discs 213. The head 238 is provided with a recess to receive an insulating pad 241. A cover 242 is secured to the housing by screws, not shown, and carries a stop screw 243, which is adjustable to vary the movements of the rod 234. A lock nut 245 is provided to secure the screw 243 in the desired position of adjustment. The cover is provided with a side opening 246 through which a clip 247 attached to the head of the rod 234 may project. A clip 248 is attached to the contactor 235. The clip 248 and contact 235 are insulated from the housing by insulation. The clip 248 as shown is connected with a resistance unit 249 which is grounded.

From the foregoing it will be observed that the

present invention has the distinct advantage that it permits the manufacture and assembly of standardized parts to form a main subassembly which may be used in making different electrical instruments for example, a voltage regulator, a current regulator, or a by-passing regulator. When it is desired to make certain of the regulators, a different coil is placed around the core and different terminal blocks are used without modification of the main subassembly. The present invention furthermore has the advantage that it permits the manufacture of different regulators which are of identical size to facilitate the assembly of different devices in containers of a certain size so that all or part of the regulators can be assembled in the case and connected without having same placed in a definite position. As an additional manufacturing advantage the apparatus of the invention dispenses with the necessity for special size regulators for special size containers that are constructed to receive a certain number of instruments.

While the embodiment of the present invention as herein disclosed, constitutes a preferred form, it is to be understood that other forms might be adopted, all coming within the scope of the claims which follow.

What is claimed is as follows:

1. A carbon pile regulator comprising, a plurality of juxtaposed carbon disc forming a stack; a housing enclosing the stack; a U-shaped magnetizable frame supported by the housing and providing pole faces; a core surrounded by a winding supported by the frame; a U-shaped bracket adjustably supported by the frame adjacent and parallel to the core; a blade hinge adjustably secured at one end to the bracket; an armature attached to the other end of the hinge; and spring means for opposing movement of the armature toward the core by magnetic force said spring having one end connected to adjustable means carried by the frame and having the other end connected with a part associated with the armature.
2. A carbon pile regulator comprising, a plurality of juxtaposed carbon disc forming a stack; a housing enclosing the stack; a U-shaped magnetizable frame supported by the housing and providing pole faces; a core surrounded by a winding supported by the frame; a bracket adjustably supported by the frame adjacent and parallel to the core; a blade spring hinge adjustably secured at one end to the bracket; an armature attached to the hinge; and a spring extending parallel to the stack and located between the housing and the U-shaped frame for opposing movement of the armature toward the core by magnetic force said spring having one end connected with the frame and having the other end connected with a part carried by the armature.
3. A carbon pile regulator comprising; a stack of discs of resistance material; a housing enclosing the stack; an electrode engaging one end of the stack and fixed relative to one end of the housing; an electrode engaging the other end of the stack and movable relative to the other end of the housing; a U-shaped magnetizable frame supported by the frame; a bracket adjustably supported by the frame; a temperature responsive leaf spring hinge adjustably attached to the bracket; an armature attached to the hinge and cooperating with the electromagnet; spring means for opposing movement of the armature toward the electromagnet; a force transmitting device under con-

trol of the spring force and the magnetic force to move the movable electrode for effecting the resistance of the stack.

4. A carbon pile regulator comprising, a fixed housing; a stack of carbon discs located within the housing; an adjustable electrode supported by the housing and engaging one end of the stack; a movable electrode engaging the other end of the stack; a magnetizable frame supported by the housing and providing pole faces; an electromagnet supported by the frame; an adjustable bracket supported by the frame; a leaf spring hinge adjustably supported at one end on the bracket; an armature cooperating with the electromagnet and attached to the other end of the leaf spring; an arm comprising side members attached to the armature and carrying a plate attached to the movable electrode said side member having openings to expose the adjustable means between the bracket and frame; means for insulating the plate from the arm; and spring means connected with the frame and the arm for urging the plate and the arm in one direction to move the movable electrode in a direction to compress the stack and opposing movement of the armature toward the electromagnet.

5. A carbon pile regulator comprising, a housing; a stack of discs of resistance material located within the housing; a magnetizable frame supported by the housing and providing pole faces; a core surrounded by a winding supported by the frame; a hinge bracket adjustably supported by the frame adjacent and parallel to the core; a leaf spring hinge adjustably supported at one end on the bracket; an armature secured to the leaf spring means for opposing movement of the armature toward the core by magnetic force; a force transmitting device under control of the spring means and the magnetic force; and means operated by the force transmitting device for effecting the resistance of the stack.

6. A carbon pile regulator comprising, a housing; a stack of discs of resistance material located within the housing; a magnetizable frame supported by the housing and providing pole faces; a core surrounded by a winding supported by the frame; a hinge bracket adjustably supported by the frame adjacent and parallel to the core; a leaf spring hinge adjustably connected to the bracket; an armature fixed to the leaf spring, spring means for opposing movement of the armature toward the core by magnetic force; a force transmitting device attached to the armature and under control of the spring means and the magnetic force; and means for effecting the resistance of the stack, said means including an electrode operated by said device and applying pressure to the end of the stack adjacent to said device, the other end of the stack remote from said device being engaged by a relatively fixed electrode supported by the housing.

7. A carbon pile regulator comprising, a housing; a stack of discs of resistance material located within the housing; a magnetizable frame supported by the housing and providing pole faces; a core surrounded by a winding supported by the frame; a U-shaped bracket supported by the frame adjacent and parallel to the core; a leaf spring adjustably on the bracket; an armature carried by the leaf spring, spring means for opposing movement of the armature toward the core by magnetic force; a force transmitting device attached at one end to the armature and under control of the spring force and the magnetic force; and means for effecting the resistance of

the stack, said means including an electrode operated by said device and applying pressure to the end of the stack, the other end of the stack being engaged by an electrode adjustably supported on the housing.

8. A carbon pile regulator comprising juxtaposed carbon discs forming a stack; a housing enclosing the stack; an electrode engaging one end of the stack and fixed relative to one end of the housing; an electrode engaging the other end of the stack and movable relative to the other end of the housing; a U-shaped magnetizable frame supported by the housing and providing pole faces; a U-shaped bracket supported by frame; a flat spring hinge adjustably attached at one end to the bracket; an electromagnet supported by the frame; an armature cooperating with the electromagnet and attached to the other end of the hinge; a U-shaped arm having its side branches attached to the armature and having the yoke connected with the movable electrode; a coil spring disposed between the frame and the housing and having one end connected to the yoke of the arm and having the other end attached to an adjustable part supported by a fixed part of the regulator, said spring opposing the movement of the armature toward the electromagnet when energized and also operating to urge constantly the movable electrode against the stack and thereby regulate the resistance of the stack.

9. A carbon pile regulator according to claim 8 wherein the spring comprises an elongated strip of spring metal having a plurality of corrugations intermediate its ends.

10. A carbon pile regulator comprising, a housing; a stack of discs of resistance material located within the housing; an adjustable electrode supported by one end of the housing and engaging one end of the stack; a movable electrode engaging the other end of the stack; a U-shaped magnetizable frame supported by the housing and providing pole faces; an electromagnet supported by the frame; an adjustable bracket supported by the frame; an armature cooperating with the electromagnet; a leaf spring resiliently supporting the armature from the bracket and capable of adjustment relative to said bracket; coil spring means for opposing movement of the armature toward the electromagnet upon energization thereof; an arm having side plates parallel respectively to the branches of the U-shaped frame and attached to the armature and having a web connecting the side plates and attached to the coil spring means; and means movable with the arm for operating the movable electrode for effecting the resistance of the stack.

11. A carbon pile regulator comprising, a plurality of juxtaposed carbon discs forming a stack; a housing enclosing the stack; a U-shaped support carried by the housing; a U-shaped magnetizable frame supported by the support and providing pole faces with the yoke of the frame adjacent the housing but spaced therefrom; a core surrounded by a winding supported by the yoke of the frame; a U-shaped bracket adjustably supported on the frame; a leaf spring adjustably supported at one end on the bracket; an armature carried at the other end of the leaf spring; a U-shaped arm attached to the armature and having side brackets straddling the bracket, said brackets having openings exposing the adjusting means between the bracket and the frame to permit adjustment of brackets relative to the frame; and spring means for opposing the move-

ment of the armature toward the core by magnetic force, said spring means being located between the housing and the yoke of the frame and having one end connected with adjustable means carried by the support and having the other end connected with a part of the arm; means for effecting the resistance of the stack, said means including an electrode carried by the arm and engaging one end of the stack, the other end of the stack being engageable by an electrode adjustably supported by the housing and means carried by the yoke of the arm for dampening the movements of the armature.

12. A carbon pile regulator comprising, a housing; a stack of resistance discs movable within the housing; a U-shaped support including a yoke and parallel branches, said branches having foot portions by means of which the support is rigidly fixed to the housing; a U-shaped magnetizable frame including a yoke portion and parallel arms providing pole faces, said arms being nested between the branches and secured thereto with the yoke of the frame spaced from the housing; a core surrounded by a winding attached to the yoke of the frame and positioned intermediate the arms of the frame; a U-shape bracket including a yoke and parallel arms, said arms straddling the branches of the support and adjustably supported thereon; a leaf spring having one end adjustably affixed to the yoke of the bracket for holding the leaf spring in a cantilever condition

relative to the yoke, an armature secured to the leaf spring and spaced by an air gap from the end of the pole faces; a U-shaped arm including parallel side portions straddling the bracket and having extending portions by means of which the arm is rigidly fixed to the armature, a coil spring for opposing movement of the armature toward the core by magnetic force, said spring being located between the housing and the yoke of the support and having one end connected to adjustable means carried by the frame and having the other end connected to the yoke of the arm; and means for effecting the resistance of the stack, said means including an electrode movable with the arm, the other end of the stack being engaged by an adjustable electrode supported by the housing.
